UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Original application filed November 16, 1921, Serial No. 515,437. Divided and this application filed June 24, 1924. Serial No. 731,987.

This invention relates to sound-deadening casings in which typewriting machines are adapted to be operated, and is a division of my application, Serial No. 515,437, filed November 16, 1921 (now Patent No. 1,521,336, dated December 30, 1924).

The invention relates to means for opening the cover of the casing when access to the interior thereof, for erasures or other purposes, is desired. Heretofore, the cover has been opened by means of a finger-piece rigidly secured to the front thereof. Such opening means, however, requires movement of the operator's hand a considerable distance from the keyboard.

Another object of the invention is the provision of means whereby the casing-cover may be opened from the immediate vicinity of the keyboard, so that the effort and time involved in the cover-opening operation may be lessened.

A feature of the invention is the employment of a lever connected to the cover and hinged to the body-portion of the casing for opening or initiating the opening movement of the cover from the vicinity of the keyboard, and of a spring-device normally ineffective to open the cover against the weight thereof, but which, when the opening movement has been initiated, becomes effective to urge the cover toward open position.

Other features of the invention relate to connections between the hand-lever, referred to, and the cover, whereby the cover may be closed against the action of the aforementioned springs; and to the mounting of the lever and operating connections, so that the lever may be brought through the front wall of the casing to such position as to present its handle-piece adjacent the keyboard; and to means for rendering sound-proof the openings in the casing-wall through which the lever and its connections pass.

Other features and advantages will hereinafter appear.

In the accompanying drawings,

Figure 1 is a view in side elevation, partly in cross-section, of a casing embodying the attachments of the present invention; the casing being partly broken away to indicate the typewriting machine, and to show certain connections therein.

Figure 2 is a top plan view, in cross-section, of the right-hand side of the casing; the cover-actuating lever being shown therein in its relation to the casing body and to the end of the typewriting machine frame.

Referring to the drawings, the casing is shown as comprising a body-portion 1, and a cover-portion 2 hinged to the body-portion at 3. The body-portion is provided with a lining indicated at 4, and the cover with a similar lining as indicated at 5. The cover is also shown as having a strip 6 of celluloid or other smooth material, to prevent the work-sheet 7 from catching on the lining. The position of the platen is indicated in dotted lines at 8 (Figure 1), on the carriage of the typewriting machine, part of the typewriter frame being shown at 9; the keyboard extension 10 of the typewriting machine protruding through a suitable opening in the front wall 11 of the body-portion of the casing. A slot 12, which extends horizontally lengthwise of the front wall of the casing-cover, is normally closed by yieldable cushions (not shown). Through this slot protrude the line-space lever 13, carriage-release lever 14, and carriage-return arm 15, which are all mounted upon the typewriter carriage and which move along the slot 12 between the yieldable body-cushions which form the same, as the carriage of the typewriting machine has its letter-feed and return movements.

Gravity normally holds the cover in the closed position upon the body-portion 1 of the casing. Spring-devices are provided, one at either side of the casing within the same, to assist the opening movement of the cover after the operation of opening the cover has been initiated, as hereinafter described. Each of these spring-devices comprises a cylinder 16, pivoted at 17 to a bracket 18 on the inside of the body-portion of the casing; and also consists of a rod or plunger 19, pivoted at 20 to a bracket 21 on the inside of the cover-portion of the casing. The rod or plunger 19 of each of the spring-devices carries a piston 22, between which piston and the end wall 23 of the cylinder 16, in which the piston operates, is a spring 26 which assists, as aforesaid, in the cover-opening operation. A buffer-spring 27, embracing the piston-rod,

19 and seated between the piston 22 and a cap 28 closing the cylinder, serves to prevent shocks to the casing when the cover arrives at open position, and to prevent 5 noises caused by said shocks. It will be understood that the positions of the pivots of the spring cover-opening devices, and the tension of the springs therein, and the proportions of the parts, are all designed so 10 that accidental opening of the cover, under the action of the springs, will not occur, and so that the springs will not offer undue resistance to the closing of the cover. For example, when the cover is closed, as shown 15 in Figure 1, the piston 22 is in such position that the spring 26 is at its greatest compression, ready to act with effectiveness as soon as the cover is partly lifted. On the contrary, when the cover is fully open, the 20 spring 26 is relaxed and therefore offers little resistance to the closing of the cover until the cover has reached such position that the weight thereof will effectively assist in the closing operation in compensation for the 25 increasing resistance offered by the spring.

The opening of the cover is initiated, and may be carried through, by means of connections as follows. Pivoted at 30 on a bracket 31, secured by screws 32 to the inside wall of 30 the casing-body, in such manner as to have vertical movement between the full and dotted line positions shown in Figure 1, is a lever 33, carrying a palm-piece 34. The rear end of the lever 33 has a pin-and-slot pivotal connection at 34*, to one arm 35 of a bell-crank lever, pivoted at 36 to a bracket 37 on the rear outside wall of the body-portion of the casing. The other arm 38 of this bell-crank lever is pivoted at 39 to an arm 40, the other end of which arm 40 is pivoted at 41 to a bracket 42 on the rear of the cover-portion of the casing. Depression of the palm-piece 34, from full to dotted line, Figure 1, position, causes the bell-crank lever 35—38 to be rocked back, drawing down the arm 40 and initiating or carrying through the movement of the cover 45 from the full to the dotted line position thereof shown in Figure 1.

50 Once the opening of the cover has been initiated by the palm-piece 34, the pivots 20 of the plungers 19 are lifted to such position that a leverage is obtained whereby the springs 26 may be effective in the cover-opening operation. When it is desired to close the cover, the palm-piece 34 may be lifted, thus causing the arms 38 and 40 to act, in effect, as a toggle, in creating an upward pressure to lift the cover, and as a linkage to swing the cover forward against the 55 resistance of the springs 26.

As shown in Figure 2, the lever-arm 33 passes through, and operates in, a suitable slot 60 in the front wall of the casing-body; 60 and a suitable stop 61, in the form of a bent

finger at the bottom of the keyboard extension of the typewriter, serves to limit the downward throw of the palm-piece 34. Two strips 62 and 63, of yieldable, resilient, sound-deadening material, such as felt, are 70 secured to the inner, front wall of the casing-body, adjacent the slot 60, and have their free edges normally abutting one another along the central line of the slot; thus closing the slot except where the opposing lips of the lining-strips are held apart by the arm of the lever. Similarly secured to the rear wall of the casing-body, adjacent the slot 65, in which the arm 35 of the bell-crank lever 75 protrudes, are two abutting strips 66 and 67, of yieldable, resilient, sound-deadening material, such as felt, for closing the slot 65 against the emission of sounds generating 80 within the casing.

Variations may be resorted to within the 85 scope of the invention, and portions of the improvements may be used without others.

Having thus described my invention, I 90 claim:

1. A sound-deadening casing for a type-writing machine, having a body-portion including front and rear walls, a cover hinged to the rear wall to swing vertically and normally maintained by gravity in closed position, the front wall of said body-portion having an opening through which the keyboard of the machine projects and also a vertical slot adjacent the side of said keyboard, a lever pivoted within said body-portion, one of the arms of the lever extending 95 through said slot to an operative position beside the keyboard, the opposite arm of the lever extending toward the rear wall, a bell-crank mounted on said rear wall, the latter having a vertical slot through which the forward arm of the bell-crank projects, a pivotal connection between said bell-crank-arm and said opposite arm of the lever, a link connecting the other arm of the bell-crank to the cover, a cylinder pivoted to the body-portion, 100 a normally ineffective spring and piston within the cylinder associated with said body-portion, and a piston-carrying rod pivoted to the cover, the spring being arranged 105 to expand against the piston, the cylinder, spring and pivots for the cylinder and rod being on a dead center when the cover is in its closed position, said lever effecting an initial raising of the cover and breaking said dead center, the spring becoming effective 110 after the breaking of said dead center to swing the cover upwardly to fully open position.

2. A sound-deadening casing for a type-writing machine, having a body-portion including front and rear walls, a cover hinged to the rear wall to swing vertically and normally maintained by gravity in closed position, the front wall of said body-portion having an opening through which the key- 115
